CHECK PAD HOLDER

Evangel A. Haveles, Los Angeles, Calif.

Application March 16, 1938, Serial No. 196,221

6 Claims. (Cl. 281—1)

My invention relates to check pad holders, particularly adapted for holding pads used for counter service such as restaurant check pads or the like, although not necessarily limited to such service, and the objects of my invention are:

First, to provide a device of this class which may be easily fastened to a counter or table and is easily and readily removed therefrom when desired;

10 Second, to provide a holder of this class having novel and simple means in connection with the holder and with a counter or table for readily and quickly securing and releasing both the holder and the counter securing means relatively to the counter or the table;

15 Third, to provide a simple check pad holder of this class which supports the check pad in position so that it is readily accessible to the user of the check pad and permits the removal 20 of one check at a time easily;

Fourth, to provide a check pad holder of this class that may be secured to a counter or table without in any way marring the counter or table at the place where it is secured;

25 Fifth, to provide a holder of this class with means for securing a string or support for a pencil in connection therewith;

Sixth, to provide a holder of this class which is very simple and economical of construction, 30 easy to shift from place to place on the counter, easy to replace pads therein, efficient in its action and which will not readily deteriorate or get out of order.

35 With these and other objects in view as will appear hereinafter, my invention consists of certain novel features of construction, combination, and arrangement of parts and portions as will be hereinafter described in detail and particularly set forth in the appended claims, reference being had to the accompanying drawing and to the characters of reference thereon which form a part of this application in which:

Figure 1 is a top or plan view of my check 45 pad holder shown positioned on a table or counter shown fragmentarily; Fig. 2 is front elevational view thereof showing the pad in position thereon; and Fig. 3 is a side elevational view thereof and showing the table or counter clamp screw fragmentarily.

Similar characters of reference refer to similar parts and portions throughout the several views of the drawing.

The counter clamp member 1, counter clamp 50 screw 2, pad holder 3, and pad holder clamp 4

constitute the principal parts and portions of my check pad holder.

The counter clamp member 1 is provided with a horizontal ledge portion 1a which rests upon the upper side at the edge of the counter C and shown best in Figs. 1 and 3 of the drawing and extends slightly past the sides of the pad holder 3. It is provided with a downwardly extending vertical portion 1b which tapers at its opposite sides as shown best in Fig. 2 of the drawing. It 15 is provided on its front face with an integral offset portion 1c, thus providing a slot at its upper edge at 1d. Positioned substantially centrally on the front face of this offset portion 1c is an integral extended loop member 1e in 20 which is adapted to be tied a string for supporting a pencil so that the pencil is always readily accessible for use on the pad. The lower side of the portion 1b is turned backwardly at 1f. This portion 1f is reinforced in its relation with the 25 portion 1b by means of two integral offset reinforcing portions 1g shown best in Figs. 2 and 3 of the drawing. Mounted in this portion 1f, which is provided with a screw threaded hole 1h, is the clamping screw 2, the one end of which 30 is adapted to fit up against the lower side of the counter C and clamp. This clamp screw is provided with a head 2a to facilitate the turning of said screw for clamping the member 1 in 35 position on the counter C. The pad holder member 3 is provided with a downwardly extending lip portion 3a at one end which is adapted to fit into the slot 1d in the upper edge of the member 1c and extend downwardly therein as shown best by dash lines in Fig. 2 of the drawing. This 40 member is also provided with upwardly extending flanges 3b and 3c which are adapted to cover a portion of the sides of the pad P when it is in position and prevent its slipping sidewise. The opposite end of the member 3 is provided with 45 a depressed portion 3d which permits this opposite end to fit down against the counter C as shown best in Fig. 3 of the drawing and compensates for the height of the member 1a on the holder 1. In this depressed portion is provided 50 a U-shaped in cross section spring clamp member 4, which fits in this depressed portion at one side at 4a and extends upwardly the height of the pad P at 4b and forms the end for the pad, and is also provided with a backwardly extending 55 spring portion 4c which fits tightly against the upper side of the pad at its clamped end, shown best in Fig. 3 of the drawing. This clamp member 4 is provided with a slot 4d in its upper side into which a portion of the upper section of the 55

pad protrudes when the pad is forced into the spring clamp member 4, thus securing the pad rigidly in position.

- 5 The operation of my check pad holder is as follows: The counter clamp member 1 is clamped in position on the edge of the counter toward the waiter or operator and the screw member 2 tightened against the lower side, the member 1a resting on the upper side. This clamp member 10 is secured in position in a convenient place for the operator. The slot at the upper edge of the member 1c receives the lip member 3a of the member 3 which fits therein and the bottom of the member 3 rests upon the member 1a and 15 on the counter backwardly from the edge some distance, and the pad with the secured end is forced into the clamp member 4 between the portions 4a and 4c and against the portion 4b. Then the operator may write on the check or 20 punch the same and tear it off at the edge of the portion 4c and it is ready for another customer. The clamp member 1 may be shifted to various positions as desired and the member 3 may be readily removed from the member 1 for replacing 25 the pads or for cleaning and both the members 1 and 3 may be readily removed from the counter for cleaning the counter when desired. The lug 1e provides means for supporting the string for a pencil.
- 30 Though I have shown and described a particular construction, combination, and arrangement of parts and portions, I do not wish to be limited to this particular construction, combination, and arrangement, but desire to include in the scope 35 of my invention, the construction, combination, and arrangement substantially as set forth in the appended claims.

Having thus described my invention, what I claim as new and desire to secure by Letters 40 Patent is:

1. In a check pad holder, the combination of a clamp member arranged to clamp over the edge of a counter provided with a horizontally positioned offset pocket portion with a slot in its 45 upper side, a check pad holder provided with a lip adapted to fit in said slot, said check pad holder provided with a U-shaped spring clip adapted to receive one end of a check pad positioned at the opposite end of said holder from said lip member.
- 50 2. In a check pad holder, the combination of a clamp member arranged to clamp over the edge of a counter provided with a horizontally positioned offset pocket portion with a slot in its upper side, a check pad holder provided with a lip 55 adapted to fit in said slot, said check pad holder

provided with a U-shaped spring clip adapted to receive one end of a check pad positioned at the opposite end of said holder from said lip member, said check pad holder provided with upwardly extending side flanges.

5 3. In a check pad holder, the combination of a clamp member arranged to clamp over the edge of a counter provided with a horizontally positioned offset pocket portion with a slot in its upper side, a check pad holder provided with a 10 lip adapted to fit in said slot, said check pad holder provided with a U-shaped spring clip adapted to receive one end of a check pad positioned at the opposite end of said holder from said lip member, said check pad holder provided 15 with upwardly extending side flanges, and a loop member in said first mentioned clamp member extending from the face thereof.

4. In a check pad holder, a counter clamp member made of thin metallic plate including a 20 horizontally disposed flange arranged to rest on the upper edge of a counter, an integral vertically disposed portion provided with an integral offset pocket portion leaving a slot at its upper edge, and enclosed at its lower edge, an integral backwardly turned portion at its lower edge, and a screw mounted in said backwardly turned portion with one end adapted to rest against the lower side of the counter.

25 5. In a check pad holder, a counter clamp member made of thin metallic plate including a horizontally disposed flange arranged to rest on the upper edge of a counter, an integral vertically disposed portion provided with an integral offset pocket portion leaving a slot at its upper 30 edge, and enclosed at its lower edge, an integral backwardly turned portion at its lower edge, a screw mounted in said backwardly turned portion with one end adapted to rest against the lower side of the counter, and a loop member on 40 the face of said counter clamp member.

35 6. In a check pad holder, a counter clamp member made of thin metallic plate including a horizontally disposed flange arranged to rest on the upper edge of a counter, an integral vertically disposed portion provided with an integral offset pocket portion leaving a slot at the upper 45 edge, and enclosed at its lowest edge, an integral backwardly turned portion at its lower edge, a screw mounted in said backwardly turned portion with one end adapted to rest against the lower side of the counter, and a check pad holder provided with a lip at one side adapted to fit in the slot in the pocket of said counter clamp member.

50 55 EVANGEL A. HAVELES.
